UNITED STATES PATENT OFFICE.

FRANK HINIKER, OF CHINESE CAMP, CALIFORNIA.

COMBINED PLOW AND SCRAPER.

1,359,376.

Specification of Letters Patent. Patented Nov. 16, 1920.

Application filed September 10, 1919. Serial No. 322,830.

To all whom it may concern:

Be it known that I, FRANK HINIKER, a citizen of the United States, residing at Chinese Camp, county of Tuolumne, State 5 of California, have invented certain new and useful Improvements in Combined Plows and Scrapers; and I do declare the following to be a full, clear, and exact description of the same, reference being had 10 to the accompanying drawings, and to the characters of reference marked thereon, which form a part of this application.

This invention relates to a combined plow and scraper, the principal object of the invention being to provide a device by means 15 of which any land may be cleared of weeds, stubble, etc.; so that it will present no dried material which might catch fire and spread to the surrounding country.

20 In this respect therefore the device is particularly adapted to be used in clearing railroad rights of way, cutting fire breaks in the mountains or elsewhere, and similar works, sweeping the cut or plowed dry 25 weeds, grass, etc. to one side as the machine progresses, and so making it impossible for the sparks of a locomotive or other steam engine to set fire to the land over which it is moving.

30 Dirt roads which have become deeply wheel rutted may be easily and quickly repaired in one operation with my improved plow and scraper, as the plow portion would cut the high spots off the road, while 35 the scraper following along would scrape and shove the same into the ruts to fill them up.

An ordinary moldboard type of plow may be attached to the frame of my device if 40 desired, in order to use the same for the particular kinds of work to which such plows are best adapted.

A further object of my invention is to mount the parts on wheels in such a manner 45 that the entire machine may travel on the wheels when being transported, and so hold the cutting and scraping edges off the ground. The wheels are also adapted to be adjusted independently to suit conditions 50 and to regulate the depth to which the plow will cut.

A further object of the invention is to produce a simple and inexpensive device and yet one which will be exceedingly effective 55 for the purposes for which it is designed.

These objects I accomplish by means of such structure and relative arrangement of parts as will fully appear by a perusal of the following specification and claims. 60

In the drawings similar characters of reference indicate corresponding parts in the several views.

Figure 1 is a side elevation of my improved device. 65

Fig. 2 is a top plan view of the same.

Fig. 3 is a fragmentary cross section through one of the auxiliary frame beams, taken on a line 3—3 of Fig. 2.

Fig. 4 is a rear end elevation of the center or main frame beam. 70

Fig. 5 is a fragmentary cross section through the other auxiliary frame beam taken on a line 5—5 of Fig. 2.

Fig. 6 is a rear end view of the plow 75 member.

Fig. 7 is a side elevation of the device fitted with an ordinary moldboard form of plow and with one of the auxiliary frames and the parts attached thereto removed. 80

Referring now more particularly to the characters of reference on the drawings the numeral 1 denotes a longitudinal rigid beam, which may be of wood, suitably reinforced with iron plates 1^a. 85

Adjacent and through the front end of this beam a standard 2 projects, having a fork 3 pivoted to the lower end, in which fork is a wide faced wheel 4 adapted to bear on the ground. Vertical adjustment of this wheel is had by means of a lever 5 connected to the upper end of the standard 2 and being pivoted to the beam 1. The position of this lever, which is adapted to be operated from the driver's seat 6 on the frame 1, is 90 maintained at any point by means of one of the usual forms of ratchet and quadrant mechanisms, as shown at 7.

Positioned closely behind the wheel 4 and in central alinement therewith and with the beam 1 is a double-faced moldboard or plow member 8 secured to the under side of the beam by means of a rigid standard 9. This plow is tri-lateral in cross section, widening out toward the rear end. The sides 8^a slope 105 outwardly toward the bottom to form cutting edges, the bottom being open.

Rigid braces 10 inside the plow member prevent any tendency to collapse. On the forward end of the upper side 8^b of the 110 plow is welded or otherwise secured a pointed knife 11.

The rear end of the beam 1 is supported by a wheel 12, permanently alined therewith, and mounted in a forked standard 13 slidable in the beam. Vertical adjustment 5 of the wheel when the device is stationary may be had by means of a pin 14 mounted in lugs 15, between which the standard 13 passes, the latter being provided with vertically spaced holes 16 that the pin 14 may be 10 inserted through any one of such holes by raising up or lowering the end of the beam 1.

Extending from the right hand side of the beam 1 substantially central of its length and at an angle of about 30 degrees thereto, 15 is an auxiliary beam 17 rigidly secured to said beam 1, there being a suitable brace beam 18 connecting the members 1 and 17 at their rear ends.

A scraper plate 19 is secured to the beam 17, 20 and depends therefrom to the level of the bottom edge of the plow 8. The forward end of the plate 19 is inserted inside the plow member 8 and riveted to one of the sides 8^a thereof, as shown at 20.

25 A wheel 21 is mounted to the rear end of the beam 17 parallel to the main beam 1, and is capable of adjustment in the same manner as the wheel 12 on the main beam, the beam 17 being provided with a rearwardly extending handle 22 in order that the same 30 may be lifted to adjust the position of the wheel.

On the left hand side of the beam 1 is another auxiliary beam 23, similarly angled 35 to the beam 1 as is the beam 17, but not rigidly connected thereto.

This beam is held in angled relation to the main beam by means of bars 24 pivotally mounted on the beams 23 and 17 in such a 40 manner that the beam 23 may have vertical movement relative to the beam 1.

Longitudinal alinement of the beam 23 is maintained by means of a rod 25 secured to the same at its forward end, and extending 45 forward to a swivel connection 26 with the beam 1, also being arranged to permit vertical play of the beam 23.

Another scraper plate 27 is secured to and depends downwardly from said beam 23, 50 extending forward to a point adjacent the rear end of the plow 8, the lower edge of such plate being adapted by reason of its allowed freedom of vertical movement, to rest on the ground at the level of the plow 55 8 at its forward end, and to follow the contour of the ground rearwardly of such forward end.

Stout bars 28 extend between the plates 19 and 27 adjacent their lower ends substantially in vertical alinement with the bars 24, and are swivelly mounted to said plates 60 as are the bars 24.

A wheel 29 is mounted to the rear end of the beam 23, in parallel alinement with the 65 beam 1, being capable of vertical adjust-

ment in the same manner as the wheels 12 and 21. A handle 30 extends rearwardly from the beam 23 in order to raise the same to adjust the wheel.

The swivel or pivotal connections of the 70 bars 24 and 28 are such that the auxiliary scraper member 27 may have practically universal movement in a vertical plane, that is, that while said member is always maintained a certain distance from the beam 1, 75 its horizontal plane may be altered relative thereto as well as its vertical alinement.

In the modification shown in Fig. 7, I have removed the auxiliary scraper member 27 and also the plow 8, and have substituted for the latter a standard moldboard plow 31, from the left or land side of which projects rearwardly a long runner 32, firmly braced to the scraper 19 as at 33, so that this bar will bear against the ground and prevent lateral movement of the scraper 19, which would prevent its proper operation.

In the operation of the device as shown in Figs. 1 to 6 when the same is to be used for clearing land of weeds etc., the wheel 90 4 is positioned at a level somewhat lower than that of the plow 8, as shown in Fig. 1, the exact amount depending on the condition of the ground. This is because the weight of the machine will cause the wheel 95 to sink into the usually loose surface ground to a certain extent, and it is not desired in this kind of work that the plow shall cut any deeper than is necessary to merely uproot or cut off the weeds etc. Of course 100 when desired, the wheel 4 may be positioned to cut any depth, such as for ditch digging, etc.

The rear central wheel 12 is adjusted so that it is about on a level with the lower 105 edges of the scraper plates 19 and 27, while the wheels 21 and 29 are raised entirely free of the ground.

Thus the rigid scraper 19 will scrape the material cut out by the plow to one side of 110 the machine, while the movable scraper 27 will do likewise, and on account of its freedom of vertical movement will be able to follow the contour of the ground whatever it may be, whether higher or lower than 115 level ground on that side, as for instance a railroad embankment.

The wheel 12 of course travels in the cleared and smooth ground between the scrapers, and the wheels 21 and 29 being 120 likewise positioned, will never come in contact with the scraped dirt on the rough area beyond the scope of the machine.

The only function of the outside wheels 125 21 and 29 is to carry the weight of the machine when transporting the same from place to place, in which event they are lowered—or the beams 17 and 23 raised—so that the lower edges of the scrapers 19 and 27 clear the ground.

As the forward end of the scraper 27 would then still be dragging on the ground, I provide a hook 34 swivelly mounted to the beam 1, which hook is adapted to fit into an orifice 35 in the plate 27 only when the latter is lifted off the ground. The hook normally rests in a horizontal position on a pin 36, but when put to service is lifted off to depend vertically, so that the weight of the plate 27 will exert a straight pull thereon.

From the foregoing description it will be readily seen that I have produced such a device as substantially fulfills the object of the invention as set forth herein.

While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

1. A combined plow and scraper comprising a longitudinal frame beam, auxiliary beams extending outwardly from the

main beam at an angle thereto, one of said auxiliary beams being swivelly mounted for vertical movement relative to the main frame, a double faced plow attached to the forward end of the main beam, and scrapers attached to the auxiliary beams whose lower edges are in alinement with the lower edges of the plow.

2. A combined plow and scraper comprising a longitudinal frame beam, auxiliary beams extending outwardly from the main beam at an angle thereto, one of said beams being rigidly fixed to the main beam, means for allowing free vertical movement of the other auxiliary beam while maintaining its angular relation with the other beam, a double-faced plow fixed to the forward end of the main beam, and scraper plates attached to the auxiliary beams and extending to the rearmost edges of the plow, and whose lower edges are substantially in alinement with the lower edges of said plow.

In testimony whereof I affix my signature in presence of two witnesses.

FRANK HINIKER.

Witnesses:

ERNEST CAPLINGER,
J. C. DE FERRARI.
